UNITED STATES PATENT OFFICE.

MIKE LUTENBERGER, OF BLOCTON, ALABAMA.

TELEPHONE SIGNALING FOR RAILWAYS.

1,085,621.

Specification of Letters Patent.

Patented Feb. 3, 1914.

Application filed August 28, 1913. Serial No. 787,218.

To all whom it may concern:

Be it known that I, MIKE LUTENBERGER, a subject of the King of Hungary, residing at Blocton, in the county of Bibb and State of Alabama, have invented certain new and useful Improvements in Telephone Signaling for Railways, of which the following is a specification, reference being had therein to the accompanying drawing.

10 This invention relates to telephone signaling for railways, and more particularly to a novel hood or transmitter and receiver holder.

15 The primary object of my invention is to provide a hood or cap that can be located in the cab of a locomotive whereby an engineer can place his head in the hood to exclude noise while a message is being received or transmitted.

20 Another object of this invention is to provide a telephonic hood or cap that can be easily placed upon the head and closed to exclude noise, whereby the receivers and transmitter can be used without any danger 25 of suffocation during the using of the hood.

A further object of this invention is to accomplish the above results by a mechanical construction, that is simple, durable, inexpensive to manufacture and highly efficient for the purposes for which it is intended.

With the above and other objects in view the invention resides in the novel construction, combination and arrangement of parts 35 to be hereinafter specifically described and then claimed.

Reference will now be had to the drawings, wherein:—

Figure 1 is a side elevation of the hood, 40 Fig. 2 is a front elevation of the same, Fig. 3 is a longitudinal sectional view of the hood.

Suspended or suitably mounted within 45 the cab of the locomotive is a hood or cap 10 (see Figs. 1, 2 and 3.) The hood or cap is made of leather or other flexible material and the sides thereof have receivers 11 connected by wire conduits 12 to a single cable 13. The front of the hood or cap has a 50 transmitter 14 and at one side of the cap is

a ventilating opening 15 having a valvular member 16 for controlling the admission and exhaust of air to and from the hood or cap. The inner walls of the hood or cap have an expansion band 17 forming a compartment 18 and this compartment can be inflated through the medium of a bulb 19. By forcing air into the compartment 18 the band 17 is expanded to frictionally grip the neck or lower part of the head to exclude noise from the hood or cap. The band 17 can be made of rubber or other expansible material. The wire conduits 12 are provided with tabs 20 which can be held to assist in retaining the hood or cap upon the head.

It is thought that the utility of the telephonic hood will be apparent without further description and while in the drawings there is illustrated a preferred embodiment 70 of the invention, it is to be understood that the structural elements are susceptible to such variations and modifications as fall within the scope of the appended claims.

What I claim is:—

1. In a telephone signaling system for railways, a locomotive equipment comprising a hood adapted to be placed upon the head, receivers carried by the side thereof, a transmitter carried by the front side of said hood, and an extensible band arranged in said hood for excluding noise from said hood.

2. In a telephone signaling system for railways, a locomotive equipment comprising a hood adapted to be placed upon the head, receivers carried by the side thereof, a transmitter carried by the front side of said hood, an extensible band arranged in said hood for excluding noise from said hood, means for ventilating said hood, and means carried by said hood for inflating said band.

In testimony whereof I affix my signature in the presence of two witnesses.

MIKE LUTENBERGER.
